TOILET SEAT HINGE

Filed April 7, 1930

UNITED STATES PATENT OFFICE

HENRY VON PHUL, OF GRAND HAVEN, MICHIGAN, ASSIGNOR TO AMERICAN BRASS NOVELTY CO., OF GRAND HAVEN, MICHIGAN, A CORPORATION OF MICHIGAN

TOILET-SEAT HINGE

Application filed April 7, 1930. Serial No. 442,092.

This invention relates to a hinge particularly adapted for use in connection with toilet seats and covers. It is a primary object and purpose of the present invention to provide a very practical, readily manufactured and assembled hinge structure which can be very easily attached and which is strong, durable and efficient for the purposes for which it is designed. An understanding of the invention may be had from the following description taken in connection with the accompanying drawing, in which,

Fig. 1 is an end elevation, partly in section, illustrating the hinge construction used in connection with a toilet seat and cover.

Fig. 2 is a fragmentary side elevation of the hinge construction shown in Fig. 1.

Fig. 3 is a perspective view of the parts used in making the hinge construction, said parts being in separated and disassembled relation, and

Fig. 4 is a fragmentary horizontal section substantially on the plane of line 4-4 of Fig. 2.

Like reference characters refer to like parts in the different figures of the drawing.

The seat and cover with which the hinge construction is used are adapted to be mounted on and above the bowl, indicated at 1, and which in practice is provided with a rearwardly extending horizontal ledge 2 at its upper end. To this ledge one member of the hinge construction is adapted to be permanently secured, two of the hinge constructions being used, one at each side and at the rear end portions of the seat and cover which are mounted above the bowl.

The hinge member, two of which are permanently secured to the ledge 2, comprises an upper member 3 which has a flat lower end to fit against the upper flat horizontal surface of said ledge 2 and from which a screw threaded bolt extension 4 passes downwardly through a suitable opening in said ledge 2 to receive a nut permanently securing the hinge member to said ledge. The upper part 3 extends upwardly and forwardly as shown and at the inner side of the upper end portion of the member 3 a horizontal open-

ing 5 is made which extends nearly through the member 3 but terminates short of its outer side. It is of course understood that when two of the hinge members 3 are attached to the ledge 2 they are in spaced apart relation to each other so that the rear end portion of the seat may pass between them.

The seat 6 is of any ordinary and conventional construction. At its rear end portion and at each side a rectangular flat block 7 of metal is secured by means of screws. This block at each side of the seat 6 has a screw threaded opening 8 therethrough as best shown in Fig. 3.

A second hinge member 9 of metal is used which at its lower portion is of channel form in cross section, having inwardly extending spaced apart vertical side flanges 10, whereby when a member 9 is placed against a side of the seat 6 and at the rear end portion thereof, the block 7 at said side of the seat is received in the recess between the flanges 10 and is completely covered by the hinge member 9. This holds the hinge members securely against any turning movement with respect to the seat and in vertical position. At their upper ends said members 9 have somewhat widened and enlarged heads 11, at the inner sides of which horizontal openings 12 are made which extend nearly through said heads.

In the lower end portions of the seat members 9 openings 13 are made which are adapted to be placed in alignment with the threaded openings 8 in the blocks 7. A headed screw comprised of a head 14 and a screw 15 of less diameter is used to attach each of the members 9 to the seat 6 by inserting the screw 15 through the opening 13 and threading the same into the opening 8 until the inner end of the shoulder between the head 14 and the screw 15 is brought snugly against the outer side of the member 9.

The seat cover 16 is of conventional construction and at its rear end is of a width to pass between the heads 11 at the upper ends of the members 9. Horizontal pins 17 are inserted in opposite sides of the rear end portion of the cover 16 and have projecting ends which are rotatably received in the openings 12 made in said heads 11 as shown in Fig. 1.

The cover and seat may be assembled by passing the upper ends or heads 11 of the vertical members 9 over the projecting ends of the pins 17 and then locking the lower ends of the members 9 over the blocks 7 and securing them in place by use of the screws 15 as described. The screws which are used to attach the blocks 7 to the seat 6 are thus covered and inaccessible and are held from any tendency to work outward. The projecting heads 14 are of cylindrical form of a size to fit freely in the openings 5 in the upper ends of the members 3. Before attaching said members 3 to the ledge 2 they are assembled over and cover said heads 14 and are then properly spaced apart to pass through the openings in said ledge.

This construction of hinge is one of very practical value. All fastening means are covered and concealed and are held against any loosening movements. The cover may turn about the axes of the pins 17 and the cover and seat together may turn on the cylindrical heads 14 which have bearings in the openings 5 in the members 3. The parts are of simple but sturdy construction, readily cast or otherwise formed and the assembly thereof is very easily accomplished. The invention is defined in the appended claims and is to be considered comprehensive of all forms of structure coming within their scope.

I claim:

1. In combination, a seat, a metal block secured adjacent one end of the seat at each side thereof, said block having a threaded opening therethrough, hinge members secured one at each side of the seat over said blocks, each of said hinge members having an opening therein in alignment with the threaded opening in the adjacent block, and securing means for each hinge member comprising a cylindrical head and a threaded shank of less diameter than the head, said shank passing through the opening in the hinge member and threading into said block whereby the head projects outwardly beyond the hinge member, said hinge members extending a distance above the seat, and a seat cover located between the upper ends of said hinge members and having a pivotal connection thereto.

2. A construction containing the elements in combination defined in claim 1, combined with a bracket located at each side of said seat, the upper end of which is provided with an opening to receive said cylindrical head, and a threaded rod extending downwardly from the lower end of each of said brackets.

3. In a construction of the class described, a seat, a block having substantially parallel vertical edges secured at each side of and adjacent one end of the seat, said block having a screw threaded opening therethrough, a vertical hinge member having a channel shaped lower end portion located over each block, securing means comprising a cylindri-

cal head and a threaded shank of less diameter, said shank passing through the opening in the hinge member and threading into the block whereby the head projects outwardly beyond said hinge member, said hinge members extending above the seat, a seat cover located at one end between the upwardly extending ends of said hinge members, and means for pivotally connecting said seat with the hinge members.

4. In combination, a seat, a flat block of metal secured at each side of and adjacent one end of the seat, said block having a screw threaded opening therethrough, a vertically positioned hinge member covering each block and located thereover and covering the securing means used in attaching the block to the seat, said hinge member having an opening therethrough located in alignment with the threaded opening in the block, means passing through the opening in the hinge member and screwing into said opening in the block, said means having a laterally projecting cylindrical portion, a seat cover located at one end between the upper ends of said hinge members, means pivotally connecting the cover to said hinge members, and a second hinge member in the form of a bracket located one at each side of the lower end portions of said hinge members and having openings to receive the projecting ends of said securing means, said brackets each at the lower end having a downwardly threaded rod adapted to pass through a projecting ledge on a bowl for securing thereto.

5. In combination, a seat, a block of substantially rectangular form of flat metal having vertical sides located one at each side of the seat and near one end thereof and having an interiorly threaded opening therethrough, screws passing through said blocks for securing the same to the seat, vertically positioned hinge members of metal, the lower portions of which are each channel shape in cross section, said lower portions of the hinge members being located over and covering the block and the screw fastening means therefor, and each of said hinge members having an opening in alignment with the threaded opening in the adjacent block, securing means comprising a cylindrical head and a threaded stem of less diameter than the head, said stem passing through the opening in each hinge member and threading into the opening in said block, whereby the cylindrical heads project laterally from said seat, said hinge members extending above the upper side of the seat, and a seat cover having one end located between the upwardly extending end portions of said hinge members combined with means for pivotally connecting the seat cover to said hinge members.

6. In combination, a seat, a block secured near one end of the seat at each side thereof, said block having a threaded opening there-

through, hinge members secured one at each side of the seat over said blocks, each of said hinge members having an opening therein in alignment with the threaded opening 5 in the adjacent block, and securing means for each hinge member comprising a head and a threaded shank of less diameter than the head, said shank passing through the opening in the hinge member and threading into 10 said block whereby the head projects outwardly beyond the hinge member, said hinge members extending a distance beyond the seat, and a seat cover located between the upper ends of said hinge members and having 15 connection therewith.

In testimony whereof I affix my signature.
HENRY VON PHUL.
